UNITED STATES PATENT OFFICE.

HAROLD M. BECK, OF EVANSTON, ILLINOIS.

INSULATING-SUPPORT FOR STORAGE-BATTERY TANKS.

1,179,395

Specification of Letters Patent. Patented Apr. 18, 1916.

Application filed November 27, 1912. Serial No. 733,738.

To all whom it may concern:

Be it known that I, HAROLD M. BECK, a citizen of the United States, and a resident of Evanston, in the county of Cook and State of Illinois, have invented certain new and useful Improvements in Insulating-Supports for Storage-Battery Tanks, of which the following is a specification.

The principal object of the present invention is to provide an insulating support for battery tanks in which the flimsy wall of the leaden or like member is protected from accidental bending or destruction, while at the same time the support shall be possessed of the necessary and usual advantages.

An embodiment of the invention is illustrated in the accompanying drawings, in which an insulating support for storage battery tanks is shown in central section.

20 In the drawings 1 is a cup member and its wall 2 is flimsy. This cup member contains an insulating liquid 3 and is usually made of lead, or like material.

4, is a cap member usually made of glass, porcelain, or like rigid material and it is provided with a rigid flange or skirt 5 depending around and protecting the flimsy wall 2 of the cup.

6, is a supporting core and it is shown as tubular and integral with the cap 4. The supporting core rests upon the bottom of the cup member and the cup member is made of lead, or like material, so as to afford a proper seat for the core which is required, 35 in many instances, to sustain a comparatively heavy load.

Inasmuch as the cup member should be made of lead, or like material, it follows that its wall 2 is flimsy or yielding and therefore 40 likely to be accidentally bent or destroyed if struck by objects, for example, a broom or other tool, or by the feet of the attendant. The skirt 5 being rigid and depending around the flimsy wall 2, protects the latter 45 from such accidental injury.

What I claim as new and desire to secure by Letters Patent is—

1. An insulating support for storage battery tanks comprising the combination of a leaden cup member adapted to form a proper seat for a heavily loaded rigid member and having a flimsy wall adapted to contain an insulating liquid, a rigid cap member seated on the leaden member and having a supporting core and having a rigid flange or skirt depending around and surrounding and protecting the flimsy cup wall from blows and the like, substantially as described. 50

2. An insulating support for storage battery tanks comprising the combination of a leaden cup member adapted to form a proper seat for a heavily loaded rigid member and having a flimsy wall adapted to contain an insulating liquid, a rigid cap member seated on the leaden member and having a tubular supporting core and having a rigid flange or skirt depending around and surrounding and protecting the flimsy cup wall from blows and the like, substantially as described. 60

3. An insulating support for storage battery tanks comprising the combination of a leaden cup member adapted to form a proper seat for a heavily loaded rigid member and having a flimsy wall adapted to contain an insulating liquid, a rigid cap member seated on the leaden member and having an integral supporting core and having a rigid flange or skirt depending around and surrounding and protecting the flimsy cup wall 75 from blows and the like, substantially as described. 80

In testimony whereof I have hereunto signed my name.

HAROLD M. BECK.
